UNITED STATES PATENT OFFICE.

DANIEL D. LOWERY, OF HARRISBURG, PENNSYLVANIA.

PUZZLE.

No. 886,999.

Specification of Letters Patent.

Patented May 5, 1908.

Application filed December 5, 1907. Serial No. 405,219.

To all whom it may concern:

Be it known that I, DANIEL D. LOWERY, a citizen of the United States, residing at Harrisburg, in the county of Dauphin and State 5 of Pennsylvania, have invented certain new and useful Improvements in Puzzles; and I do declare the following to be a full, clear, and exact description of the invention, such as will enable others skilled in the art to 10 which it appertains to make and use the same.

My invention relates to puzzles.

The object of the invention is to provide a puzzle which will be cheap to manufacture, 15 which is comparatively hard to work out and yet is always amusing and entertaining.

With this object in view, the invention consists of certain novel features of construction, combination and arrangement of parts 20 as will be described hereinafter and particularly pointed out in the appended claims.

In the accompanying drawings, Figure 1 is a top plan view with the cover in position; and Fig. 2 is a top plan view with the cover 25 removed. Fig. 3 is a section on line 3—3 of Fig. 1.

Referring more especially to the drawings, 1 represents a rectangular box having a top, 2, secured thereto in any suitable manner, so as to be fixed with relation to the box, and which is provided with a plurality of apertures, 3, here shown as three in number. 30 These apertures register with and uncover chambers, 4, 5, 6, the rest of the apparatus 35 in the box being closed from inspection by the top, 2. The compartments, 4, 5, 6, are defined by side walls, 7, which extend around throughout the box, and form channels or raceways, 8, 9, 10, 11, 12 and 13, and also 40 blind chambers, 14, 15 and 16. The side walls extend up to a point approximately level with the upper edges of the box and may be curved in any suitable manner, but are preferably formed as herein shown.

45 A partition, 17, extending from one of the walls, 7, to the side of the box 1 is provided to form chambers, 18 and 19, for the reception of the playing balls, 20, and to prevent these playing balls from hanging in corners, 50 all partitions are rounded at their corners, and corner pieces, 21, are provided.

The only part of the working which is seen is at the moment the balls, 20, which represent trains entering the stations. The legends, "Station No. 1," "Station No. 2," 55 and "Station No. 3," are placed adjacent the apertures, and Station No. 1 always indicates the starting point of the round trip. The balls are first held within Station No. 1, and one at a time are started out and carried 60 around to Station No. 2. The same operation is followed in carrying the balls from Station No. 2 to Station No. 3, and from Station No. 3 back to Station No. 1.

It will be seen that the channels which are 65 formed by the side walls, 7, and the sides of the box, are invisible to the operator, and it is, therefore, rather difficult to manipulate, the balls so that they may be placed in the 70 succeeding stations.

From the foregoing description, taken in connection with the accompanying drawings, the construction and operation of the invention will be readily understood without requiring a more extended explanation. 75

Various changes in the form, proportion and the minor details of construction may be resorted to without departing from the principle or sacrificing any of the advantages of the invention, as defined in the appended claims. 80

Having thus described my invention, what I claim as new and desire to secure by Letters-Patent, is:

In a puzzle, a box, a plurality of raised ribs equaling in width the depth of the box 85 and forming tortuous or serpentine communicating passage-ways or channels, chambers or compartments having entrance ways communicating with said passages or channels, a plurality of balls adapted to be moved within said passage-ways, and a removable opaque cover for the box having unobstructed apertures registering with the compartments. 90

In testimony whereof I have hereunto set my hand in presence of two subscribing witnesses. 95

DANIEL D. LOWERY.

Witnesses:

PAUL SANDERS,
BUD LEREW.
